LOOSE LEAF BINDER

Glenn H. Ehlke, Chicago, Ill.

Application January 18, 1954, Serial No. 404,458

1 Claim. (Cl. 129—24)

My invention relates to loose leaf binder mechanism, the instant application being an improvement over my patent designated 2,661,004 issued December 1, 1953.

An important object of my invention is to provide a loose leaf binder which is adapted to hold a number of sheets or pages removably assembled therein.

Another object of my invention is to provide a device of the aforementioned character in which loop elements, on which the leaves or loose pages are mounted, are unbroken and of substantially semi-circular configuration, the same being also provided with beveled ends to facilitate assembly and removal thereof.

A still further object of my invention is to provide a binder structure of the aforementioned character which can be readily opened for insertion thereinto, or removal therefrom, the pages having perforations to fit the binder loop elements.

A still further object of my invention is to provide a loose leaf binder mechanism which is equipped with loop elements each being provided with retaining notch means adjacent their ends, so that the said loop elements may be opened on right or left hand sides of the loose leaf mechanism, in order to permit the loops to be opened and/or completely removed from the binder mechanism.

A still further object of my invention is to provide a mechanism of the aforementioned character in which more or less loop elements may be optionally utilized depending on the binding requirements.

A still further object of my invention is to provide in a device or mechanism of the aforementioned character locking ledges which are articulately mounted so that either of the said ledges may be rotated substantially within an arc of 180° when closing the folder structure, or within an angle of 90° for the removal or insertion of loose leaf pages when one end of the loop elements is freed from engagement.

A still further object of my invention is to provide locking ledge means which are equipped with transverse partially cylindrical notches, the said loop elements being also provided adjacent their ends with transverse partially cylindrical locking notches and locking rods provided with manipulating portions, the said locking rods being adapted to optionally engage in locking relationship the transverse locking notches on the said loop elements and being further provided with flat portions so that when the said locking rod elements are rotated 180°, substantially, the flat portions thereof will permit release from locking engagement of the locking notches of the said loop elements.

A still further object of my invention is to provide eye bolt means secured in resilient relationship to the said swinging or locking ledges in order to mount therein rotatably the said locking rod elements.

A still further object of my invention is to provide a loose leaf structure which is simple in its construction, practical for the purposes for which it is purported to be used, and one which can be manufactured economically in quantity production.

2

Other objects and ancillary advantages resident in my invention will become apparent from an examination of the accompanying drawings having further reference to the ensuing description for explanation of the construction and operation of the invention, in which like symbols are used to designate like parts, and in which:

Fig. 1 is a perspective view of my invention showing certain portions thereof broken away.

Fig. 2 is a cross-sectional view taken, substantially, on the line 2—2 of Fig. 1.

Fig. 3 is a cross-sectional view taken, substantially, on the line 3—3 of Fig. 1.

Fig. 4 is a fragmentary and enlarged view of the locking means illustrated in Fig. 2, shown in release, or in position to free one end of the locking loop elements.

Fig. 5 is a cross-sectional view taken, substantially, on the line 5—5 of Fig. 3.

Referring to the various views my invention is generally designated 6 and consists of a cover structure having a right hand cover element 7 and a left hand cover element 8 interconnected by a central back bone section 9, being also provided with the weakened portions 10 so as to provide flexure and articulate connection between the cover elements 7 and 8 and the back bone 9.

The binder mechanism consists of a number of loop elements 14 of substantially semi-circular configuration provided with the beveled ends 17 to facilitate locking assembly and release from locking position. The said locking loop elements 14 are provided with transverse partially cylindrical notches 18 adjacent their ends 17, and the same are engaged in locking engagement by the locking rods 19 provided with the manipulating handle portions 20. The locking rod elements 19 are provided with flat portions 21 which act as a release when rotated to the position indicated in Fig. 4 so that the locking notch 18 is not in locking engagement with the locking rod 19. The loop elements are inserted in locking notches 13 which are cut transverse to the body of the swinging ledges 12, the ledges 12 being articulately connected to the back bone section 9 by means of suitable hinges 11.

The locking rod elements 19 are maintained in operative position by eye bolts 26 which are secured to the locking ledges 12 by means of lock nut 23 provided with spanner holes 25 to facilitate assembly of the eye bolts 26 and the nuts 23, the nuts 23 being further provided with a centrally located tapped hole 24 for securing the threaded extension 27 of the eye bolts 26. A resilient washer 28 of rubber or like material is interposed between the eye bolt 26 and the locking ledge 12 so as to furnish a braking action to the locking rod elements 19. The lock nuts 23 are fitted within nesting bores 22 in ledges 12.

Thus, when it is desired to insert pages into the binder mechanism one of the ends is released as indicated by the dotted lines of Fig. 2 by rotating the handle portion 20 from its locked position to the release position as indicated in Fig. 4, one end of each and every loop element 14 may be released and other pages inserted. In like manner, either the end 15 or 16 may be released. In Fig. 2 end 15 is shown released. End 16 may be released while end 15 is maintained in locking engagement, thus permitting articulation of the hinge element 11 on the right hand side of Fig. 2 and vice versa the hinge element on the left may be operated while the end 15 is released whereas the hinge element 11 on the right may be articulated when the end 16 of the loop element 14 is released. If both ends 15 and 16 are released the manipulating handles 20 of the lock rods 19 are rotated outwardly as contrasted with their inward locking position, in which event the flats 21 afford release from engagement of the locking rod bodies by virtue of the alignment of the flat 21, thus permitting complete removal of the loop

elements 14. Notches 13 are provided approximately an inch, or an inch and one quarter apart throughout the length of the locking ledges and since the flat 21 exists practically throughout the entire length of the locking rod 19 as many loop elements 14 or as few loop elements 14 may be distributed over the length of the binder mechanism in order to afford rigid security to the contents that are bound.

When thinner pages are mounted it would be apparent that more loop elements 14 should be utilized. When 10 more rigid pages are mounted such as photographs on heavy Bristol board or paper, fewer loop elements 14 would be required.

I believe I have herein illustrated and described the nature of my invention, and expounded, in expository form, the teachings so that those familiar with the art will be able to practice my invention. Inasmuch as the same is susceptible of many modifications, alterations, and improvements, I hereby reserve the right to any improvements, alterations and modifications coming within 15 the scope and spirit of my invention and disclosure, also the right to any improvements impliably embraced in the accompanying illustrations depicting the generally suggested elemental structure of my invention, and also any modifications, improvements, or alterations, falling within the purview of the foregoing description; my invention to be limited only by the subjoined claim.

Having thus described and revealed my invention, what I claim as new and desire to secure by Letters Patent is:

Loose-leaf binder mechanism, comprising cover means 30 including right hand and left hand cover elements, flat

back bone means disposed intermediately the said cover elements, right hand and left hand locking ledge elements provided with inner edges and bottom edges and mounted 5 parallelly with said inner edges facing one another, hinge elements securing articulately the said bottom edges of the said ledge elements to the said back bone means, the said ledge elements being provided with transverse notches along the said inner edges, a multiplicity of eye bolt elements secured to the said inner edges with the eye portions thereof positioned in co-axial alignment, substantially cylindrical locking rod means rotatably mounted in the said eye bolt elements, loop elements removably secured in the said transverse notches and provided with transverse notches adjacent their termini engageable releasably by the cylindrical surfaces of the said locking rod means, continuous longitudinal flat portions on the said locking rod means adapted to release from locking engagement the said locking rod means with respect to the said last-mentioned transverse notches when the said locking rod means are rotated substantially 180°, and manipulating portions on the said locking rod means.
